Atty's.

UNITED STATES PATENT OFFICE

BENJAMIN F. HARTWELL, OF WINCHESTER, MASSACHUSETTS

APPARATUS FOR PRODUCING CREPE RUBBER SPRING-HEELED SHOE BOTTOMS

Application filed January 29, 1929. Serial No. 385,951.

This invention relates to the production of spring-heeled shoe bottoms composed of crepe-rubber, each bottom including a full length sole member having a face constituting a heel seat, and a heel member having a heel seat-engaging face adhesively united to said heel seat. The said faces are usually rendered adhesive by the application thereto of a solvent, such as a benzol solution, which 10 gelatinizes the faces, the members being then united by superimposing one of said faces on the other, and exerting pressure on the members to cause an intimate union of the adhesive faces.

15 The chief object of the invention is to enable spring-heeled shoe bottoms, characterized as above stated, to be produced more rapidly and accurately than by the methods heretofore practiced.

20 Other objects will hereinafter appear.

The invention consists in the improved apparatus for producing spring-heeled crepe-rubber shoe bottoms hereinafter described and claimed.

25 Of the accompanying drawing forming a part of this specification,—

Figure 1 is a top plan view, showing an apparatus embodying the invention, a breast- 30 ing machine being indicated by dotted lines.

Figure 2 is a side view of the same.

Figure 3 is a section on line 3—3 of Figure 1.

Figure 4 is an end view, looking toward the delivering end.

35 Figure 5 shows separately and in perspective, the sole and heel members of a spring-heeled shoe bottom.

Figure 6 is a longitudinal section of the 40 incomplete shoe bottom produced by the apparatus.

Figure 7 is a longitudinal section of the bottom as completed by the breasting machine indicated by Figures 1 and 2.

45 The same reference characters indicate the same parts in all of the figures.

In the drawing, 12 designates an endless conveyor which is a belt mounted on a driving drum 13, driven by a motor 14, and on a loose drum 15, said drums being journaled in bearings on fixed standards 16. A speed reducer

associated with the motor, is indicated at 17 (Figures 1 and 4), the organization being such that the speed of the driving means is regulable so that the conveyor may be driven at a suitably slow rate of speed, in the direction indicated by the arrow in Figure 1 to enable operators to manipulate the work as hereinafter described, while it is being carried by the conveyor. The said regulable driving means also enables the conveyor belt 55 to be driven at different speeds according to the hygrometric condition of the atmosphere, for a purpose more fully explained herein-after.

60 The upper stretch of the conveyor is substantially horizontal, its top surface facing upwardly, and including a receiving portion, designated by *a*, whereupon crepe-rubber shoe bottom members 21 and 23, having gelatinized surfaces may be separately and loosely deposited, a delivering end portion, designated by *b*, and an intermediate end portion, designated by *c*, whereon said members may be assembled to unite the gelatinized surfaces 65 thereof preparatory to the transportation of the assembled members to the delivering portion.

65 The top surface of the upper stretch is unobstructed from end to end to permit said separately deposited and assembled members, which I call the work, to be transported from end to end of the conveyor while resting loosely thereon, and to be manipulated at any point between the ends of the conveying stretch.

70 Longitudinal edges of the receiving portion *a* and the intermediate portion *c*, are unobstructed to provide, beside said portions, stations for operators positioned to separately deposit the members on the receiving portion, and to assemble the members on the intermediate portion.

75 Located beside an operator's station 1, at one edge of the receiving portion *a*, is a solvent-applying mechanism, designated as a whole by 18, and including, in this instance, a trough containing the solvent 19, and rolls 20 and 21, the roll 20 being rotated in the trough by any suitable means. The rolls are 80 arranged to permit the heel end of a sole 21 to 85

100

be passed by the operator through the nip of the rolls and receive a coating 22 (Figure 5) of solvent covering the face of the sole which constitutes a seat for the heel 23, the coating gelatinizing said face and rendering it adhesive. The operator then deposits the sole on the receiving portion *a* with the adhesive face uppermost and exposed.

Located beside an operator's station 2, at the opposite edge of the receiving portion *a*, and preferably diagonally opposite the mechanism 18, is another solvent-applying mechanism, designated as a whole by 24, and including, in this instance, a tank 25, containing the solvent, and rolls 27 and 28, through the nip of which a second operator at the station 2 may pass the heel 23, and cause the heel seat-engaging face of the heel to receive a coating 29 of solvent covering said face, the roll 27 being driven by any suitable means. Each of the solvent-applying mechanisms may be otherwise organized, if desired.

The operator at station 2 deposits the heel on the receiving portion *a* beside a sole deposited by the first operator and with the adhesive face uppermost and exposed.

The progressive movement of the conveyor is continuous, and causes an accumulation of soles and heels thus deposited, in rows located side by side, as shown in Figure 1.

The apparatus includes means for applying a localized air blast to the exposed adhesive faces of the soles and heels, while they are progressing from the station 2, to evaporate the excess solvent and render said faces tacky and cause the quick adhesion to each other. Said means, as here shown, includes a motor-driven blower, whose casing is designated by 30, and a flue 31, extending from the blower to a point over the conveyor, and provided with a distributing nozzle 32, adapted to discharge air downwardly upon the conveyor and its load, at a location between the portions *a* and *c*.

An assembling operator's station 3 is provided at one edge of the intermediate portion *c* between the delivering end thereof and the nozzle 32, where a third operator may act, by picking up and inverting the heels, and depositing the tacky faces thereof on the tacky faces of the heel seats, so that the soles and heels are assembled, incomplete shoe bottoms in the condition shown by Figure 6, being provided. The incomplete bottoms are moved in a single row by the conveyor, from the station 3, toward the delivering portion *b*.

The apparatus may be adapted for use in applying trade labels to the sole members of the incomplete bottoms, said labels being usually disks 34 of soft vulcanized rubber, having indicia on their outer sides.

To permit this operation, I provide an operator's station 4, at one edge of the intermediate portion *c*, where a fourth operator may act, by applying any suitable cement to

the inner sides of the labels and depositing the labels on the shank portions of the sole members of the incomplete bottoms.

When the apparatus is adapted for the last mentioned use, it comprises means for applying a localized air blast to the labels and to the surrounding portions of the soles, to dry any cement that may be exposed on said surrounding portions. Said means may include a flue 35, connected with the blower casing, and having a distributing nozzle 36, arranged to direct air downwardly on the label-carrying portions of the sole members, said nozzle being between the station 4 and the delivering portion *b*.

The heel member of each incomplete bottom prepared as above described, has a beveled breast face 37, overhanging a portion of the sole, as shown by Figure 6.

Each bottom may be completed by a subsequent operation performed by a breasting machine adapted to conform a portion of the sole to the breast face 37, as shown by Figure 7, and at the same time, press the contacting adhesive faces of the sole and heel firmly together. The breasting machine, indicated by dotted lines in Figures 1 and 2, and designated as a whole by 38, is disclosed by my Patent No. 1,738,533, dated December 12, 1929. Said machine may be located in such proximity to the delivering end of the conveyor, that the operator may transfer incomplete bottoms from the conveyor to the breasting machine for treatment by the latter.

Among the advantages of the described apparatus, are the following:

Each of the manual operations is performed by a single operator, who does nothing else, and becomes proficient in the performance of the one operation, so that rapidity and accuracy of production by team work are ensured.

The air-blast applying means causes quick and automatic drying of the parts acted on thereby.

The progressively moving conveyor may be adapted to accumulate, support, and advance a considerable number of separated soles and heels, and any desired number of incomplete bottoms, and deliver the latter to the operator of the breasting machine which completes the bottoms.

It will be seen that each incomplete bottom in the condition shown by Figure 6, may be completed as shown by Figure 7, by a single operation involved by the presentation of the incomplete bottoms, one at a time to the breasting machine, by a final operator located at the station designated by 5, in Figure 1, the operator being in position to transfer the incomplete bottoms from the delivering end of the conveyor to the breasting machine.

The completing operation may be per-

formed as fast as the incomplete bottoms reach the delivering end of the conveyor.

The belt portion *c* hereinbefore called the intermediate portion, is in fact, an assembling portion, and is so called in the appended claim.

The above-mentioned regulable means is adapted to drive the pulley 13 at different speeds and progressively move the belt 12 at different speeds, according to the hygrometric condition of the surrounding air, and thereby cause a relatively slow speed and a relatively long exposure of the gelatinized surfaces to the air blast which renders said surfaces tacky, when the humidity of the air is relatively high, and a faster speed and a longer exposure of said surfaces to the air blast when the humidity is relatively low. The apparatus is therefore variable to compensate for all changes of the humidity of the surrounding air, and ensure suitable tackiness of the gelatinized surfaces under all hygrometric conditions.

I claim:

25 Apparatus for use in preparing crepe rubber spring-heeled shoe bottoms composed of separately formed soles and heels, said apparatus comprising an endless conveyor belt, pulleys supporting said belt and providing it with a substantially horizontal upwardly facing upper stretch which is elongated to provide a receiving portion whereon the soles and heels may be separately deposited, an assembling portion whereon the soles and 35 heels may be assembled, and a delivering portion, the width of the belt being such that soles and heels treated with a solvent to gelatinize surfaces thereof, may be separately deposited on the receiving portion, with 40 their gelatinized surfaces exposed, means for directing an air blast against the upper stretch at a location between the receiving and assembling portions, to evaporate excess solvent and condition the gelatinized surfaces 45 for quick adhesion to each other on the assembling portion, and regulable means for driving one of said pulleys to progressively move the belt at different speeds, according to the hygrometric condition of the surrounding air, and thereby cause a relatively slow speed and a relatively long exposure of the gelatinized surfaces to the air blast when the humidity of the air is relatively high, and 50 a faster speed and a shorter exposure of said surfaces to the air blast when the humidity of the air is relatively low, the top surface of the upper stretch being unobstructed to permit manipulation of the work thereon, 55 longitudinal edges of the receiving and assembling portions being unobstructed, to provide stations at opposite sides of the receiving portion for operators positioned to 60 separately deposit the soles and heels on said portion, and a station for an assembling op-

erator positioned to assemble said soles and heels on the assembling portion.

In testimony whereof I have affixed my signature.
